CASE CHANGING MECHANISM FOR
TYPEWRITERS

Gary Frank Turner, Boscobel, Wis.

Application October 21, 1952, Serial No. 315,869

4 Claims. (Cl. 197—80)

This invention relates to typewriter construction, and more particularly, has reference to the means provided upon a typewriter for elevating and lowering the platen cradle thereof to upper and lower case positions.

Conventionally, the means provided upon a typewriter for the purpose described above is so designed as to require that it be operated by the little fingers of the typist's hands. Substantial force must be exerted, in this connection, by the little fingers in elevating the platen cradle, to overcome the weight of the cradle, and thus, it is my observation that the conventional construction is such as to require that the hardest work be done by the little fingers, with the lightest work being done by the thumbs of the hands. The thumbs, of course, are much stronger than the little fingers, and it is therefore the main object of the present invention to provide an improved case changing means for typewriters which will be particularly arranged for actuation by the thumbs, rather than by the small fingers of the hands.

It is another important object of the present invention to provide a case changing mechanism of the type stated which will not only be designed for actuation by the thumbs, but will also be so designed as to permit a single case-change bar to be used, both for elevating the platen cradle and for holding the platen cradle releasably in its elevated position. In conventional typewriter constructions, separate keys must be provided, namely, a shift key and a shift lock key, one of the keys being adapted only for elevating the cradle, and the other key, namely, the shift lock key, being both for elevating and releasably locking the cradle in its elevated position.

Other objects will appear from the following description, the claims appended thereto, and from the annexed drawing, in which like reference characters designate like parts throughout the several views, and wherein:

Figure 1 is a perspective view of the main frame of a typewriter, the platen cradle thereof, and the case changing means constituting the present invention, a portion of said main frame being broken away;

Figure 2 is an enlarged, detail sectional view taken substantially on line 2—2 of Figure 1, the case-change bar being shown in the depressed position thereof, as it appears when the platen cradle is not to be locked in elevated position;

Figure 3 is a transverse sectional view, also taken on line 2—2 but looking in the opposite direction, the case-change bar being shown in its cradle-locking position;

Figure 4 is a fragmentary perspective view of the case-change bar and of one of the levers supporting the same, said bar and lever being disassembled from one another; and

Figure 5 is a fragmentary top plan view of the front portion of a typewriter, showing the case-change bar in the relation that it bears to the letter keys and space bar of the machine.

Referring to the drawing in detail, the reference numeral 10 has been applied generally to a typewriter, said typewriter having a main frame 12. Since the main frame 12 is of conventional construction, it will not be described in detail. It will be understood, in this connection, that in Figure 1, only the main frame and those parts that necessarily cooperate with the present invention have been illustrated, for the purpose of clarity.

Mounted upon the rear portion of the main frame 12 is a platen cradle 14 on which is supported the conventional platen 16, said platen cradle 14 being mounted for

2

up and down movement to upper and lower case positions.

The typewriter is equipped with the usual keys 18 and space bar 20.

The parts so far illustrated and described are wholly conventional, and do not, per se, constitute part of the present invention.

The invention has been designated generally by the reference numeral 24, said invention comprising a case changing means adapted to be operated by a user for elevating and lowering the platen cradle 14.

In accordance with the present invention, a pivot pin 26 is provided, said pin extending between the respective side walls of the main frame 12, at a location intermediate the front and back of the typewriter. At its opposite ends, the pin 26 is engaged in aligned openings formed in said side walls, said pin being also extended through openings formed in a pair of parallel levers 28.

The levers 28, as shown in Figure 1, extend longitudinally of the respective side walls of the main frame, said levers being spaced inwardly a short distance from said side walls. The levers 28 are thus pivoted about a common axis represented by the pin 26, said levers swinging in parallel, vertical planes. As will be noted from Figure 1, the pivot axis of the levers 28 is disposed intermediate the opposite ends of the levers, but is closer to the front ends of the levers, that is, those ends disposed adjacent the front of the typewriter, than it is to the back ends of the levers.

Formed in the back ends of the levers 28 are openings receiving connecting pins 30, said pins 30 extending through the lower ends of substantially vertical, parallel links 32. The links 32 extend upwardly along the respective side walls of the main frame, and at their upper ends are connected to the opposite ends of the platen cradle 14.

It will thus be seen that if the front ends of the levers 28 are depressed, the rear ends thereof will rise, shifting the links 32 upwardly in the direction of their lengths, thus to elevate the platen cradle. Normally, the platen cradle tends to gravitate to a lower position, and will so gravitate when a positive force is not applied to the front ends of the levers, tending to depress the same.

Formed upon each lever 28, at the front end of the lever, is a short, upstanding extension 34 (Figure 4), the extensions 34 of the levers having openings 36. The openings 36 register with openings 38 provided in depending extensions 40 of a case-change bar 41.

Pivot pins 42 extend through the registering openings 36, 38, thus to mount the case-change bar 41 upon the levers 28 for pivotal movement about an axis extending in parallelism with the longitudinal center line of the case-change bar.

In this way, the case-change bar is mounted to rock transversely upon the front ends of the levers 28, between a position shown in Figure 2, and a position shown in Figure 3.

As will be noted from Figures 1 and 5, the case-change bar is elongated, extending substantially from side to side of the typewriter, in closely spaced, parallel relation to the conventional space bar 20 of the machine. Accordingly, the case-change bar 41 is disposed for depression by the thumbs, rather than by the small fingers, of a user's hand, and when the case-change bar is depressed, it will be effective to cause elevation of the platen cradle 14.

Secured to the underside of the case-change bar 41, adjacent the opposite ends thereof, are apertured lugs 44, and hooked at their upper ends in the lugs 44 are springs 46. The springs 46 are hooked at their lower ends in the upstanding extensions 34 of the levers 28, said springs being of the coiled, contractile type. Thus, the springs will tend, when the case-change bar is rocked to the position thereof shown in Figure 3, to resist said movement of the case-change bar in this direction, and the springs will thus provide means for normally holding the case-change bar in the position thereof shown in Figure 2.

Formed upon the lower end of each extension 40 of the case-change bar is a laterally projected lug 48, said lug 48 extending into the path of the upstanding extension 34 of its associated lever 28. The lug 48 limits

swinging movement of the case-change bar from the position thereof shown in Figure 3 to the position thereof shown in Figure 1, the lug 48 engaging the extension 34 to prevent the return spring 46 from pulling the case-change bar 41 beyond the normal, horizontal position thereof.

Immediately above the lug 48 of each extension 40 is a notch 50, said notch 50 complementing, and being adapted to receive, a detent 52 provided upon a bracket 54. The brackets 54 are projected inwardly of the main frame, from the front wall of the typewriter, and are fixedly secured to said front wall. Normally, the detents 52 do not interfere with depression of the case-change bar 41, said detents being disposed out of the path of downward movement of the extensions 40 of the case-change bar, when said extensions 40 are disposed vertically as in Figure 2.

By reason of this arrangement, one is permitted to depress the case-change bar 41 for elevating the platen cradle momentarily, without locking the platen cradle in its elevated position.

If, however, it is desired to lock the platen cradle in its elevated position, the user, after depressing the case-change bar 41, exerts a lateral pressure upon said bar, tending to rock the bar in the direction of the user, that is, in the direction of the low front wall of the main frame.

When this is done, the case-change bar will be rocked transversely as shown in Figure 3, with the lower end of each extension 40 swinging toward the detent 52 adjacent thereto. As a result, the respective detents 52 will engage in the notches 50 of the depending extensions 40 of the case-change bar, thus to hold the case-change bar in its depressed position and thereby lock the platen cradle 14 in its elevated position.

At such time as the cradle is to be unlocked, it is necessary only that a lateral pressure be exerted upon the case-change bar 41, in the direction of the platen cradle. This causes the detents 52 to be disengaged from their associated notches 50, thus permitting the springs 46 to contract, in a manner effective to return the case-change bar 41 to its normal position shown in Figure 2. As a result, the case-change bar 41 is permitted to rise, with the platen cradle dropping to its lower position.

It is seen from the above that the construction of the invention is such as to permit movement of the platen cradle between its upper and lower positions, responsive to thumb pressure exerted by the user, rather than by finger pressure exerted by the little fingers of the user's hands. Further, the construction is such as to embody in the bar 41 not only a thumb-receiving key for elevating the platen cradle, but also a combination shift key and shift lock key, this construction being distinguished from that of conventional typewriters, wherein it is usual to provide a shift key separate from a shift lock key.

It is believed apparent that the invention is not necessarily confined to the specific use or uses thereof described above, since it may be utilized for any purpose to which it may be suited. Nor is the invention to be necessarily limited to the specific construction illustrated and described, since such construction is only intended to be illustrative of the principles of operation and the means presently devised to carry out said principles, it being considered that the invention comprehends any minor change in construction that may be permitted within the scope of the appended claims.

What is claimed is:

1. In a case-changing mechanism for a typewriter, the combination with a main frame and with a platen cradle mounted thereon for up and down movement between upper and lower case positions, of a pair of levers arranged longitudinally of opposite sides of the frame and mounted thereon to pivot about a common, horizontal axis; a case-change bar pivotally connected at its opposite ends to one end of the respective levers and arranged for depression by a user to rock the levers about said pivot axis thereof, the other ends of the levers having a connection to the platen cradle for elevating the cradle responsive to depression of said bar by a user; and detent means carried by the main frame and arranged to releasably engage said bar in the depressed position thereof, to hold the cradle in its elevated position.

sition, said detent means being disposed to engage the bar on pivotal movement of the bar in one direction upon its associated levers while in said depressed position.

- 5 2. In a case-changing mechanism for a typewriter, the combination with a main frame and with a platen cradle mounted thereon for up and down movement between upper and lower case positions, of a pair of levers arranged longitudinally of opposite sides of the frame and mounted thereon to pivot about a common, horizontal axis; a case-change bar pivotally connected at its opposite ends to one end of the respective levers and arranged for depression by a user to rock the levers about said pivot axis thereof; links extending upwardly along the opposite sides of the frame and pivotally connected at their opposite ends to the other ends of the levers and the cradle respectively, for elevating the cradle responsive to depression of said bar by a user; and detent means carried by said main frame and arranged to releasably engage said bar in the depressed position thereof, to hold the cradle in its elevated position, said detent means being disposed to engage the bar on pivotal movement of the bar in one direction upon its associated levers while in said depressed position.
- 10 20 25 30 35 40 45 50 55 60 65 70 75
3. In a case-changing mechanism for a typewriter, the combination with a main frame and with a platen cradle mounted thereon for up and down movement between upper and lower case positions, of a pair of levers arranged longitudinally of opposite sides of the frame and mounted thereon to pivot about a common, horizontal axis; an elongated case-change bar extending substantially from side to side of the main frame and connected at its opposite ends to one end of the respective levers for pivoting on the levers about an axis paralleling the longitudinal center line of the bar, said bar being arranged for depression by a user to rock the levers about said pivot axis of the levers; links extending upwardly along the opposite sides of the frame and pivotally connected at their opposite ends to the other ends of the levers and to the cradle, respectively, for elevating the cradle responsive to depression of said bar by a user; and detent means carried by the main frame and arranged to releasably engage said bar in the depressed position thereof, to hold the cradle in its elevated position, said detent means being disposed to engage the bar on pivotal movement of the bar in one direction upon its associated levers while in its depressed position.
4. In a case-changing mechanism for a typewriter, the combination with a main frame and with a platen cradle mounted thereon for up and down movement between upper and lower case positions, of a pair of levers arranged longitudinally of opposite sides of the frame and mounted thereon to pivot about a common, horizontal axis; an elongated case-change bar extending substantially from side to side of the main frame and connected at its opposite ends to one end of the respective levers for pivoting on the levers about an axis paralleling the longitudinal center line of the bar, said bar being arranged for depression by a user to rock the levers about said pivot axis of the levers; links extending upwardly along the opposite sides of the frame and pivotally connected at their opposite ends to the other ends of the levers and to the cradle, respectively, for elevating the cradle responsive to depression of said bar by a user; stationary detents carried by the main frame, said bar having depending extensions formed with detent-receiving notches, said notches and detents providing means to hold the cradle in its elevated position, said detents being disposed to engage in the notches on pivotal movement of the bar in one direction upon its associated levers while in its depressed position; and springs connected between the extensions and levers and tensioned to normally bias the bar out of its detent-engaged position.
